UNITED STATES PATENT OFFICE.

FRANK M. SANDERS, OF RED ROCK, OKLAHOMA.

TRACTOR SHIELD.

Application filed September 1, 1922. Serial No. 585,748.

To all whom it may concern:

Be it known that I, FRANK M. SANDERS, a citizen of the United States, residing at Red Rock, in the county of Noble and State of Oklahoma, have invented new and useful Improvements in Tractor Shields, of which the following is a specification.

Tractors extant and more particularly certain well known tractors embody powerful air fans that subject the operators thereof to objectionable blasts of hot air and dust.

The object, therefore, of my said invention is the provision in a tractor of a shield, susceptible of ready application, and possessed of the capacity of deflecting the blast of hot air and dust from the tractor fan down around the motor, thereby relieving the eyes and body of the operator from heat and dust.

To the attainment of the foregoing, the invention consists in the improvement as hereinafter described and definitely claimed.

In the accompanying drawings, forming part of this specification:—

Figure 1 is a side elevation showing a portion of a well known make of tractor equipped with my novel shield.

Figure 2 is a detail plan view with the fuel tank of the tractor removed to better show the arrangement of my novel shield.

Figure 3 is a longitudinal vertical section showing the inter-position of my shield between the motor and the fuel tank.

Figure 4 is a transverse section taken in the plane indicated by the line 4—4 of Figure 2 and showing the preferred configuration of the forward portion of the shield.

Figure 5 is a longitudinal section on the line 5—5 of Figure 2, showing the preferred form of shield.

Figure 6 is a plan view of the blank from which is formed the shield constituting the best practical embodiment of my invention of which I am cognizant.

Similar numerals of reference designate corresponding parts in all of the views of the drawings.

The well known make of tractor alluded to comprises among other elements a motor 1 of internal combustion type, a fuel tank 2 above the motor and in spaced relation thereto, and a fan casing 3 in front of the motor. The operator's station is behind the motor and fuel tank in convenient proximity to the steering wheel designated by 4.

In accordance with my invention I pro-

vide a shield 5 preferably in the form of a metallic plate of twenty four gauge, the said plate being of general rectangular form and being interposed between the motor 1 and the fuel tank 2, Figures 1 and 2, so as to effectively guard and protect the operator against the blast of hot air and dust that the fan in the casing 3 tends to throw rearwardly. The shield 5 in the performance of

the said function acts after the manner of a baffle to deflect the hot air and dust downwardly about the motor 1, and in order to enable the shield to better serve the purpose I provide the rear end and the side edges of the shield with pendent flanges numbered 6 and 7, respectively. I also curve the forward portion of the shield transversely as best shown in Figure 4 at 9 and 9^x; and the portion of the forward end of the shield

between the forward extensions designated by 9^z, I curve upwardly as designated by 9^a in Figures 3 and 5. Thus the shield intercepts and deflects the blast from the fan downwardly and in that way averts subjecting the operator to discomfort and injury so that he is better able to steer the tractor and operate the same to the best advantage.

This will be better understood when it is stated that in virtue of the forward upward curvature 9^a, all of the blast from the fan is caught and prevented from passing over the shield, and is caused to follow the curve and move under the shield. The curve or flange

6 at the rear end of the shield catches the blast and deflects the same downward. The intermediate curvature 9, Figures 3, 4 and 5 accommodates the fuel tank 2; and it will be readily appreciated that the said depression or curvature 9 guides the air and dust to the curved portions 9^x and the flanges 7. These

portions 9^x and flanges 7 extend laterally outward to a sufficient extent to catch all of the fan blast and concentrate the same inwardly with the result that escape of portions of the blast past the edges of the shield is precluded.

In other words the shield transversely curved as illustrated acts as a hood above the blast; and has the effect of maintaining a strong draft of air downwardly upon and around the motor block which conduces to cooling of the motor.

The forward extensions 9^z of the shield serve to concentrate and gather in all of the air directed rearwardly by the fan, and for such reason I prefer to employ the said extensions 9^z.

For use in the type of tractor illustrated, the shield is provided with forward tongues 8, an aperture 9°, in its body adjacent to but spaced from its rear end, and a notch 10 in 5 its rear end and adjacent to though spaced from its right hand edge. The said tongues 8 are adapted to be readily introduced between the front bail 11 of the tractor and the projection 12, Figure 3, subsequently to the 10 loosening of the front bail nuts. Then when the said nuts are turned tight the forward end of the shield will be strongly and securely fastened in position snugly against the said projection. I provide the 15 notch 10 in the rear end of the shield to receive the air-washer pipe 13 of the tractor, Figure 2, and the aperture 9° serves to receive and to enable the rear portion of the shield to rest on the usual comparatively 20 large part of the conduit 14 between the fuel tank 2 and the motor 1; the said conduit being made up of detachably connected members which are connected together subsequently to the positioning of the shield. 25 Manifestly when arranged as stated the rear portion of the shield is adequately supported and held against casual lateral movement.

In addition to the prime advantage ascribed to my novel shield, the same serves secondarily to shed rain and thereby prevent the same from detracting from the efficiency of the wiring and coils of the motor.

It will be apparent from the foregoing 35 that the shield may be stamped from sheet metal, Figure 6 and may then be appropriately flanged or shaped as shown in Figures 4 and 5.

My novel shield is adapted to be used to 40 advantage in all tractors, and it is within the purview of my invention to appropriately build the shield formed of any material compatible with its purpose in a tractor at the time of manufacture thereof 45 or to install the shield in a tractor after the manufacture of the latter. In either case the shield will guard the operator, more particularly his feet and legs against heat, and will effectively protect his face and eyes 50 against dust, sand grit and the like and will obviate the necessity of the operator inhaling dust.

While my improved shield is calculated 55 to materially increase the sale of tractors by meeting the mentioned objection frequently offered against the make of tractors illustrated, it will be appreciated that the shield is inexpensive and is adapted to be quickly and easily installed in tractors at present in 60 use without the necessity of invoking the assistance of skilled labor.

I have entered into a detailed description 65 of the construction and relative arrangement of the parts embraced in the present and preferred embodiment of my invention

in order to impart a full, clear and exact understanding of the said embodiment. I do not desire, however, to be understood as confining myself to the specific construction and relative arrangement of parts inasmuch 70 as in the future practice of the invention various changes and modifications may be made such as fall within the scope of my invention as defined in my appended claims.

Having described my invention, what I 75 claim and desire to secure by Letters-Patent, is:—

1. A tractor having a motor, a fan casing in front of the motor, and an operator's station back of the motor, and also having 80 a shield positioned to protect the operator against the blast of hot air and dust maintained by the fan by deflecting said blast; the said shield being arranged above the motor and having pendent flanges at its 85 rear end and side edges and also having a forward portion with a central depression the forward end of which is directed upwardly.

2. A tractor having a motor, a fan casing in front of the motor, and an operator's station back of the motor, and also having 90 a shield positioned to protect the operator against the blast of hot air and dust maintained by the fan by deflecting said blast; 95 the said shield being arranged above the motor and having pendent flanges at its rear end and side edges and also having a forward portion with a central depression the forward end of which is directed upwardly; said forward portion arranged between forward, side extensions.

3. As a new article of manufacture, a shield for the purpose described having pendent flanges at its rear end and side edges 105 and also having a forward upwardly-directed portion at the forward end of a transversely curved or dished portion.

4. As a new article of manufacture, a shield for the purpose described having pendent flanges at its rear end and side edges and also having a forward upwardly-directed portion at the forward end of a transversely curved or dished portion, said upwardly directed portion between the rear 115 portions of forward side extensions.

5. As a new article of manufacture, a shield for the purpose described equipped at its forward and rear ends with tongues and apertures, respectively, and also equipped 120 at its rear end and side edges with pendent flanges, one of the said apertures being in the form of a notch in the rear end flange.

6. The combination with the motor, fuel 125 tank and front bail of a tractor, the motor and fuel tank being connected by a conduit, and the tractor being provided with an air-washer pipe, of a shield having forward spaced tongues secured in said bail and also 130

having a rear notch and an opening receiving the air-washer pipe and the conduit, respectively.

7. The combination with the motor, fuel tank, and front bail of a tractor, the motor and fuel tank being connected by a conduit, and the tractor being provided with an air-washer pipe, of a shield having forward spaced tongues secured in said bail and also having a rear notch and an opening receiving the air-washer pipe and the conduit, respectively; the shield being flanged at its rear end and side edges and curved upwardly at its forward end and having a transversely-dished forward portion.
8. The combination with the motor, fuel

tank, and front bail of a tractor, the motor and fuel tank being connected by a conduit, and the tractor being provided with an air-washer pipe, of a shield having forward spaced tongues secured in said bail and also having a rear notch and an opening receiving the air-washer pipe and the conduit, respectively; the shield being flanged at its rear end and side edges and curved upwardly at its forward end and having a transversely-dished forward portion, and also having forward side extensions.

In testimony whereof, I affix my signature.

FRANK M. SANDERS.
